UNITED STATES PATENT OFFICE

129,616

DESIGN FOR A SHOE

Donelson Caffery Glassie, Chevy Chase, Md.

Application October 1, 1940, Serial No. 95,542

Term of patent 14 years

To all whom it may concern:

Be it known that I, Donelson Caffery Glassie, a citizen of the United States, residing at Chevy Chase, in the county of Montgomery and State of Maryland, have invented a new, original and ornamental Design for a Shoe, of which the following is the specification, reference being had to the accompanying drawing, forming a part thereof.

In the drawing:

The figure is a perspective view of a shoe, showing my new design.

I claim:

The ornamental design for a shoe, as shown.

DON CAFFERY GLASSIE.
